UNITED STATES PATENT OFFICE.

CHARLES C. MILLER, OF FORT WAYNE, INDIANA.

PACKING-TRAY.

1,188,192.

Specification of Letters Patent. Patented June 20, 1916.

Original application filed January 13, 1915, Serial No. 1,962. Divided and this application filed June 5, 1915. Serial No. 32,286.

To all whom it may concern:

Be it known that I, CHARLES C. MILLER, a citizen of the United States, residing at Fort Wayne, in the county of Allen and 5 State of Indiana, have invented new and useful Improvements in Packing-Trays.

The invention relates to packagers for various articles and particularly to such devices adapted for use in packing articles 10 in bags.

In my application Serial No. 1,962 I describe and claim a method of packaging laundry in which process the device of the present application enters and the present 15 application is a division of said previous application.

An expensive part of a laundry establishment is the time and materials consumed in packing the laundry for delivery. The 20 usual practice heretofore has been to place the shirts in covers and then wrap all the articles in paper, or to place the articles in a knock-down box which must first be set up. All these steps require time and storage 25 space for the boxes, and the likelihood of soiling the laundry by the operator's hands which are apt to become soiled in assembling the boxes. Also the paper wrapped packages have no protection against collapse and crushing of the articles within.

The object of my invention is to provide a novel means for packaging various articles in bags or other receptacle with great rapidity so as to form a neat package in which 35 the contents are protected.

In the drawings I illustrate the preferred form of my invention, although said form may be varied in certain details without departing from the spirit of my invention, 40 and in said drawings.

Figure 1 is a plan view in perspective of the packing tray; Fig. 2 a longitudinal sectional view of the same in use and Fig. 3 a plan view in perspective of a package 45 which has been made upon the device.

Referring to the drawings the packing or charging tray consists of a scoop-like structure 10, preferably made of thin metal and having a bottom 11 the forward end of 50 which is preferably rounded, the bottom also having a rib 12 extending transversely across its lower side. There are two side walls 13 and an end wall 14 which connects the side walls. A depending flange 15 may be provided at the rear by which the device may

be secured to a table 16 or other desirable or convenient object, a thumb screw 17 serving to clamp the flange to the object. Any suitable means for securing the device will suffice. When a flat surface is beneath the device the rib 12 serves to elevate its forward end so that a receptacle may be passed over the device. The tops of the forward ends of the side walls 13 slope upwardly from their forward extremities so that said walls 60 are comparatively low at their forward ends and gradually increase in height a desired distance from said ends. From the summit of the slope to the rear the top edges of the sides may be continuous in height with said 65 summit, but they are preferably lower than said summit as shown in Fig. 1.

In use the articles to be packed are placed upon the tray and the receptacle 18, which is preferably a bag having a normally open 70 mouth, is drawn over the tray and its contents. The operator is merely required to bring the mouth of the bag up into engagement with the curved end of the tray which effects the primary opening of the bag, and as he draws the bag toward the rear of the 75 tray the sloping sides fully open the said mouth and permit of the ready placing of the bag over the tray. End wall 14 prevents the articles which have been deposited upon the tray from slipping therefrom as the bag is drawn over the tray. A great deal of 80 time is thereby saved in the operation and tearing of the mouth of the bag is practically eliminated. It is understood, of course, that the mouth of the receptacle is 85 not smaller than a cross-section through the tray at the highest point of its sides.

In Fig. 2 I illustrate the use of the tray in a laundry where a rectangular reinforcing 90 rim 19 is adapted to be inserted into the bag together with laundried articles, the rim being first placed on the tray and the articles within the rim. The bag is drawn over the tray and its contents and then the 95 bag with the rim and articles within it is removed from the tray; and the mouth of the bag is then closed and the package shown in Fig. 3 is ready for delivery.

What I claim is:

1. A packing tray comprising a substantially horizontal bottom, means to support said member at one end thereof leaving the opposite end free and unobstructed and vertically disposed members secured to each 100

side edge and one end edge of the bottom for the purposes described.

2. In a device of the character described, a flat member located in substantially horizontal position, means to support said member at one end thereof leaving the opposite end free and unobstructed, and upwardly projecting members attached at each side edge of said member to provide a place therebetween in which articles of wear may be positioned and serve as means to guide bags over said articles substantially as described.

3. A packing tray comprising a bottom member having upwardly extending walls 15 at its opposite side edges, a depending member at one end of the bottom adapted to be secured to a fixed object and a depending rib on the bottom adapted to coöperate with the depending member to support the said bottom in substantially horizontal position and leave the other end of the bottom free and unobstructed for the purposes described. 20

In witness whereof I hereunto subscribe my name this 3d day of June, 1915.

CHARLES C. MILLER.
